(57) **CLAIM**

The ornamental design for a weighted golf club grip, as shown and described.

DESCRIPTION

FIG. 1 is a perspective view of a weighted golf club grip showing our new design.

FIG. 2 is a front view thereof.

FIG. 3 is a rear view thereof.

FIG. 4 is a top view thereof.

FIG. 5 is a bottom view thereof.

FIG. 6 is a left side view thereof; and,

FIG. 7 is a right side thereof.

The broken line showing of golf grip is included for the purpose of illustrating and forms no part of the claimed design.
